UNITED STATES PATENT OFFICE.

CARL L. NILSON, OF TRANScona, CANADA.

LOCOMOTIVE.

1,093,069.

Specification of Letters Patent. Patented Apr. 14, 1914.

Application filed April 28, 1913. Serial No. 764,000.

To all whom it may concern:

Be it known that I, CARL LORENTZ NILSON, a subject of the King of Sweden, residing at Transcona, Canada, have invented 5 certain new and useful Improvements in Locomotives, of which the following is a specification.

My invention relates to locomotives, and its objects are principally to increase the 10 power of traction by imposing more of the existing weights of engine and tender upon the driving wheels; to redistribute the weight of the engine so as to bring a portion thereof closer to the track; to prolong 15 the exposure of the boiler to the heat of the gases of combustion; to exhaust or blow off condensed steam in the cylinders into the smoke stack, and to provide such other improvements as will appear from the detailed 20 description, such as moving back the forward cylinders for the general purpose of the invention.

With the above-named objects in view the invention consists in the novel construction 25 of engine and the arrangement of its parts, all as hereinafter described in detail, illustrated in the accompanying drawing and incorporated in the appended claims.

In the drawing—Figure 1 is a side elevation partly in section of a locomotive embodying my invention. Fig. 2 is a section 30 taken substantially on line X—X of Fig. 1 with the steam cylinders omitted.

In the drawing 2 represents the boiler provided with a steam dome 3 from which leads 35 a steam pipe 4 to a steam chest 5 from which the cylinder 49 is supplied with steam, both sides of the locomotive being substantially alike. From the usual smoke box 6 into which the usual flues 7 lead, one or 40 more flues 8 lead rearwardly into an auxiliary smoke box 9 which has its outlet through a stack 10 immediately in front of the engine-man's cab 11. A drop door or 45 closer 12 is provided for the usual smoke stack 13 to close the latter in order to direct the gases of combustion rearwardly through the stack 10 when only light firing is required. This is for the purpose of economizing fuel by exposing the boiler to a prolonged heating by the escaping gases. The flue or flues 8 have their rearward ends over the fire place 14. The door 12 is controlled 50 by a lever 15 connected with a rod 16 the forward end of which is pivoted to a lug 17 on the door 12. A rearwardly extending

branch 18 of the steam pipe 4 admits steam to a steam chest 19 for the rear cylinder 20 mounted on the tender truck 21 carrying the tender 22, having the water tank 23 and coal space 24, the particular form of construction of which is not involved in the present invention.

For the purpose of shifting the center of mass, or center of gravity so called, of the engine or locomotive nearer to the track and thus improving its stability against swaying, I equip the locomotive with one or more tanks such as 25 and 26 which are arranged in suitable vacant spaces between the axles of the drive wheels. These tanks have fluid connections with each other, the details of which are immaterial and not shown, and supplement the tank 23 as a source of water-supply. The latter and the tank 25 are shown connected by pipes 27 and 28. The latter has its rear end bent upwardly in a portion 29 which leads through centrally apertured swivel-bearing plates 30 and 31 forming the pivotal or king bolt 32 connection between the body 22 of the tender and its truck 21. To the end of the portion 29 of the pipe 28 is swiveled by any of the usual flexible joint connections a pipe 32 which leads the water from the side tank 23 to the axial bearing of the tender.

33, 34, 35 and 36 represent the side-bearings between the body of the tender and its truck and same are shown as of the well known roller type. The blow-off of steam and water through the cylinder cocks often bespatter and annoy passengers walking past an engine at a station platform and in the present invention I have remedied this difficulty by providing the cylinder cocks 37 with a conduit pipe 38 which leads into the smoke box 6.

Separate levers for link motion-connections with the usual eccentric rods may be provided for the locomotive and its tender, but I have shown means for operating link motions for both by a lever 38 to which is pivoted at one side of its fulcrum 39 a rod 40 for the locomotive link while a rod 41 for the tender link is pivoted to the lever 38 at the opposite side of its fulcrum as shown in Fig. 1. 42 and 43 represent, respectively, the well known form of bell crank lever for the locomotive and tender link. The reversing mechanism or link motion which would be coupled to these bell cranks at 44 and 45 in each instance is not shown, same being of

usual and well known construction and forming no part of the present invention. 46 represents the steam control for the steam pipe 4 and its extension 18, said lever 46 being connected by a rod 47 with a valve 48 controlling the steam flow through the pipe 4, the exact details of which are non-essential. The essential feature of the valve 48 is that it controls the flow from the pipe 4 to the pipe 18, or, in other words, controls the admission of steam to the rear cylinder 20 and its companion on the opposite side. The details of steam admission to the forward or locomotive cylinder 49 and its companion are not shown, as this invention requires no change in the usual throttle and its connections and a particular description of this as well as several other well known parts which are the usual parts of a locomotive structure require no description in this connection. The draw-bar coupling between locomotive and tender is represented at 50 and the pipe 29 is substantially the axis upon which the tender body is permitted to swing relative to the truck in rounding curves to the desirable slight extent. The wheels 51, 52, 53 and 54 of the tender are all shown as employed for traction purposes, hence these wheels together with the locomotive drivers 55, 56, and 57 carry the entire weight of locomotive and its tender and the auxiliary gravity tanks 25 and 26.

In lieu of the usual forward truck one of the functions of which is said to be to relieve the cylinders from a portion of the initial blows or impacts that the forward wheels receive, I have placed the cylinder 49 about six feet in the rear of its usual position, or, as shown in Fig. 1, between the first and second drivers 55 and 56 which removes the cylinder from the position of greatest strain and substantially makes the driver 55 serve as the forward truck while also serving as a traction wheel.

In climbing heavy grades my invention with the usual equipment of engine and tender is designed to increase the traction power 60 per cent. or more, or, in other words, make the tender and its heavy weight serve as an auxiliary engine by manipulating the lever 46 to admit steam to the rear

cylinders. The weight of locomotive or engine usually imposed upon the forward truck, having small wheels which do not assist the traction power, is in the present invention utilized by transferring the locomotive body projection beyond the drivers to the rear of the driver or drivers 57 and supporting the rearward projection upon the tender truck. The point of support of the rear of the engine on the tender is indicated at 58 and is simply the usual pivotal bearing which is on the tender truck 21 the tender body 22 being, as previously explained, revoluble relative to the truck to a limited extent on the axis represented by the pipe portion 29.

Having thus described my invention I claim as new and desire to secure by Letters Patent—

1. The combination with a locomotive and its tender carrying the supply of fuel and water for said locomotive, of a water tank forming a part of said tender, a water tank forming a part of said locomotive and arranged below the boiler of said locomotive, and means providing fluid connection between the tender water tank and the tender forming a part of said locomotive, whereby the tender and locomotive tanks are connected as a single tank and a part of the water supply is utilized as weight for the locomotive as specified.

2. The combination with a locomotive of the smoke box into which the boiler flues of the locomotive have their outlets at the front end of the locomotive, a substantially similar smoke box at the rear end of the locomotive boiler, flues connecting the front and rear smoke box, and an outlet or smoke stack for the latter.

3. The combination with a locomotive and its cylinder cocks, of means for exhausting through said cylinder cocks and the smoke stack of said locomotive.

In testimony whereof I have hereunto set my hand in the presence of two subscribing witnesses.

CARL L. NILSON.
